KNOCK OUT BOTTOM

Filed March 14, 1929

INVENTOR.
William Salisbury

BY

Thos. Donnelly
ATTORNEY.

UNITED STATES PATENT OFFICE

WILLIAM SALISBURY, OF TOLEDO, OHIO

KNOCK-OUT BOTTOM

Application filed March 14, 1929. Serial No. 346,883.

My invention relates to a new and useful improvement in a knockout bottom used particularly in the pottery industry for serving as a bottom of the mold in which pots and similar receptacles are formed and also used in removing the formed receptacles from the female die after the spinner has performed its function and been raised from operating position.

10 The present invention is an improvement of my invention on a knockout bottom for which I have filed application for United States Letters Patent by my application Serial Number 302,742 filed August 29, 1928.

15 It is an object of the present invention to provide in a knockout bottom having a rotatable member, resilient means for supporting the rotatable member in operative position so arranged and constructed as to prevent a minimum obstruction so that clay and other material passing through the female die, may be free to drop so as not to interfere with the moving parts.

20 It is another object of the invention to prevent a clogging of clay or other material from which the receptacles are made in a position so as to interfere with the free rotation or axial movement of the bottom.

25 Other objects will appear hereinafter.

30 The invention consists in the combination and arrangement of parts hereinafter described and claimed.

35 The invention will be best understood by a reference to the accompanying drawings which form a part of this specification, and in which,

Fig. 1 is a side elevational view of the invention showing it applied.

40 Fig. 2 is a central vertical sectional view of the invention.

Fig. 3 is a view taken on line 3—3 of Fig. 2 with parts broken away.

45 In the drawings, I have illustrated a table 7 on which is supported the female die 8 in which a spinner (not shown) is adapted to engage for spinning and forming the plastic material to conform to the shape of the female die 8 and of the proper thickness. After the spinning operation, it is desired that the 50 formed article in the female die 8 may be

removed therefrom. Engaging the inwardly projecting flange 9 of the die 8 are lugs 10 which project outwardly from the retainer 11 which is threaded onto the knob 12, in which is threaded the actuating rod 13. The bottom 14 is provided with the centrally extending shaft 15, which is fixedly mounted thereto and which extends through the bushing 16, positioned in the retaining member 11. A bolt 17 is threaded into the lower end of the shaft 15 and engages a washer 18 which engages the end of the bushing 16. A plurality of slideable pins 19 are projected through the bottom 14, each of these pins being provided with a head 20 which engages the disc 21, having the boss 22 which engages in a peripheral groove 22' formed axially in the bushing 16. Secured to the end of the retainer 11 and projecting upwardly therefrom in spaced relation, are leaf springs 23 which engage the under surface of the disc 21 and serve to retain the pins 19 thrust outwardly beyond the outer surface of the bottom 14. The bottom 14, together with the shaft 15, is rotatable relatively to the retainer 11, thus carrying the pins 19 rotatably, so that a pot placed in the die 8 and through the bottom of which the pins 19 may project, will, if and when rotated by the spinner, carry with it the rotatable bottom 14, so that the perforations formed in the bottom of the pot will be the size of the pins 19 and no deformation effected. The springs 23 give the necessary yieldability to the bottom 14, and it will be noted that the bottom of the screw 17 is spaced from the end of the member 13 so that the shaft 15 may be, if required, moved axially relatively to the retainer 11 against the tension of the springs 23.

With a knockout bottom formed in this manner the formation of articles, or containers, such as pots and the like, with a plurality of openings in the base, may be fabricated on the automatic machines now customarily used and an economical construction of such articles effected.

By mounting the springs 23 on the lugs 10 instead of forming these lugs as a peripheral flange, a minimum obstruction is presented

so that clay and other material sliding downwardly of the bottom 14, will be permitted to pass downwardly along the retainer 11, so that as not to accumulate between the disc 21 and the upper edge of the retainer 11. Thus, the disc 21 is free to function and move axially as the springs 23 are normally kept free from foreign material.

The region between the lugs 10 serve as clearways for the clay or other plastics to pass through to be discharged from the mold. There is of necessity, sufficient space between the rotary bottom 14 and the female die side wall to permit free rotation of the bottom. While in practice, this may be but a few thousandths of an inch, it is large enough to permit a small amount of the plastic to be forced therethrough by the pressure of the spinner in forming the article. To prevent any accumulation on the flange 9 below the member 14 and in the region of the springs 21, the clearway regions between the lugs 10 are provided. The retainer proper is also spaced from this flange 9 so that the clay which leaks through the space between the rotary member 14 and the die side wall may continue downwardly between the lugs 10 and clear the die through the space between the edge of the flange 9 and the retainer 11. The retainer, in its lowermost position, is supported by the flange 9 by means of the lugs 10 resting thereon. The spring, ring and pin mechanism is thereby maintained free from any plastic accumulations.

While I have illustrated and described the preferred form of my invention, I do not wish to limit myself to the precise details of structure shown, but desire to avail myself of such variations and modifications as come within the scope of the appended claims.

Having thus described my invention, what I claim as new and desire to secure by Letters Patent is:

1. In a knockout bottom of the class described, a retaining member, a rotatable base, pins slidably projected through said base, a plate for engaging the lower ends of said pins, lugs mounted on said retaining member and projecting outwardly from the periphery thereof, a support engaged by said lugs to have a clearway between said support and retaining member, and springs secured to said lugs and engaging said plate for normally retaining said pins in operative position.

2. In a pottery mold, a die providing a support, a retainer carried by said support, and a rotatable die member mounted on said retainer, there being a clearway provided between said support and retainer.

3. In a pottery mold, a die providing a support, a retainer provided with an overhang cooperating with said support to mount said retainer thereon, said overhang providing a clearway between said support and re-

tainer and a bottom forming die carried by said retainer.

4. A plant pot mold comprising a side wall forming die, a bottom forming die relatively rotatable thereto, a retainer mounting said die supported by said side wall die and having a clearway region therefrom.

5. In a pottery forming die, a rotatable member, a retainer for said member, means for mounting said retainer leaving a clearway between said retainer and mounting means.

6. In a pottery forming die, a rotatable bottom forming member, mounting means for said rotatable member comprising radially extending spaced lugs, and a support engaging the termini of said lugs to provide a clearway between said mounting means and support.

7. In a pottery forming die, a rotatable bottom forming member having a depending shank, a bearing for said shank provided with a series of radially extending lugs, and mounting means for said lugs whereby a clearway region is provided between said mounting and bearing.

In testimony whereof I have signed the foregoing specification.

WILLIAM SALISBURY.
